UNITED STATES PATENT OFFICE.

WILLIAM B. ROWLAND, OF BAKERSFIELD, CALIFORNIA.

CROWN BLOCK FOR WELL-DRILLING APPARATUS.

Application filed March 6, 1923. Serial No. 623,145.

To all whom it may concern:

Be it known that I, WILLIAM B. ROWLAND, a citizen of the United States, residing at Bakersfield, in the county of Kern, and

5 State of California, have invented certain new and useful Improvements in Crown Blocks for Well-Drilling Apparatus, of which the following is a specification.

My invention relates to the general art 10 of well-drilling apparatus, and particularly to what is known as the crown-block assembly, surmounting the derrick, and carrying the various sheaves for the several operating lines.

15 The object of my invention is to provide a simple, rigid and effective crown-block, especially one in which the sheaves may be adjusted readily as to position; and to this end my invention consists in the novel 20 crown-block assembly which I shall now fully describe by reference to the accompanying drawings, in which—

Fig. 1 is a plan view of my crown-block.

Fig. 2 is a side elevation of the same.

25 Fig. 3 is an end view of the structural frame of the crown block, from which the sheaves and their supporting shafts and clamps have been omitted.

30 Fig. 4 is a section on the line 4—4 of Fig. 2.

Fig. 5 is a section on the line 5—5 of Fig. 4.

The structural frame of the crown block, 35 comprises a plurality of parallel spaced beams 1, spacing members 2 at each end, and tie-bolts 3. Upon the beams 1 are fixed the non-rotatable shafts 4 which support and upon which rotate the several sheaves of the operating lines. In the present case for the 40 sake of illustration, the beams 1 are five in number, and they are, as usual of I-cross section Figs. 3 and 4.

The spacing members 2 are short sections 45 of I-beams, set on edge, with their flanged ends fitting against the webs of adjacent main beams 1, as seen in Figs. 1 and 3. The tie-bolts 3, which are best arranged in groups of four, Fig. 2, pass through the webs of the main beams 1, and through the flanged ends 50 of the spacing members 2, two bolts of said group, one above and one below, lying on each side of the web of said spacing members.

55 The frame thus made is essentially rigid, and well adapted for the purpose. The sheaves here shown are the usual ones, such,

for example, as the sand-line sheave 5, the casing-sheaves 6, the drilling-line sheave 7 and any others employed in the art. Each of these sheaves is rotatively mounted on its 60 appropriate fixed shaft 4 by means of its hub, which is fitted with a bushing 8, Fig. 4. The journal portion 4' of the shaft is of circular cross section and preferably enlarged, while the ends of the shaft are flattened on 65 their lower sides, Fig. 2, to lie firmly on top of the I-beams 1 of the structural frame. The shafts 4 are held on the beams by a pair of complementary clamps. Each clamp comprises a body portion 9, the face of which is curved 70 on the radius of the shaft, a flat foot portion 9^a with inwardly directed hooks 9^b on each side, and a head portion 9^c. One of these clamps lies on each side of each end portion of the shaft, the body portion 9 of the clamp 75 fitting the side of the shaft, the flat foot portion 9^a resting on the flat top of the upper flange of the beam 1, its hooks 9^b slidably embracing the edges of said flange, and its head portion 9^c receiving a bolt 10 which 80 connects the pair of clamps together. A set screw 11 is fitted through the foot portion of each clamp and bears on the top of the beam 1. A feature of these clamps to be especially noted is that the faces of their 85 body portion 9, which bear on the sides of the shaft are convexed or crowned laterally as indicated at 12 in Fig. 5.

The pair of clamps thus associated with the beams and with the shafts, 90 not only provide an effective, firm fastening for the shafts, without the necessity of making holes in the beams as would be required by the use of bolts, but also, they enable the shafts to be placed 95 in any desired position on the beams, and to be set at an angle thereto if and when required, since the clamps can be slipped along the beam to desired position, and, due to their rounded bearing faces, one 100 pair of clamps at one end of the shaft can be set forward or back of the other pair at the other end, the shaft rocking on the rounded clamp face to accommodate its resulting angularity relatively to the beams, 105 and this adjustment may be effected without having to make any holes in the beams.

On account of the rotative mounting of the sheaves on the shafts, and the relatively inaccessible position of the crown-block, the 110 matter of journal lubrication assumes a peculiar importance. In this connection I

have made the shafts 4 with a longitudinal bore 4" the ends of which are normally closed by screw plugs 13. Fig. 4. From the middle lower portion of the bore 4" are made radially directed holes opening out on the lower surface of the journal portion 4' of the shaft, and in these holes are driven tightly wooden oil pervious pins 14. Figs. 4 and 5. In the shaft is made a hole 15 from the periphery inwardly to the bore 4" and in this hole is fitted an oil filler cup 16. Fig. 4. The lubricant thus passes from the cup 16, through the hole 15 into the shaft bore 4", and thence it passes 15 through the grain of the wooden pins 14 to the sheave journal.

I claim:

1. A crown-block comprising spaced, parallel, flanged beams; a sheave-sustaining shaft resting upon said beams; clamps embracingly fitted to the shaft said clamps having flat-foot-portions resting on the beams with hooks slidably embracing the beam-flanges, adapting said clamps for adjustment along said beams, to vary the position of the shaft thereon; and set screws fitted to the clamp foot-portions for fixing the clamps on the beams in adjusted position.
2. A crown-block comprising spaced, parallel, flanged beams; a sheave-sustaining shaft resting upon said beams; and a pair of complementary clamps embracingly fitted to the sides of the shaft, said clamps resting on the beams and having hooks slidably embracing the beam flanges adapting the clamps for adjustment along said beams, to vary the position of the shaft thereon, and a binding bolt fitted between the tops 40 of the clamps above the shaft.
3. A crown-block comprising spaced, par-

allel, flanged beams; a sheave-sustaining shaft resting upon said beams; a pair of complementary clamps embracingly fitted to the sides of the shaft, said clamps having foot-portions resting on the beams and having hooks slidably embracing the beam flanges adapting the clamps for adjustment along said beams, to vary the position of the shaft thereon; a binding bolt fitted between the tops of the clamps above the shaft and set screws fitted in the clamp foot-portions for fixing the clamps on the beams in adjusted position.

4. A crown-block comprising spaced, parallel, flanged beams; a sheave-sustaining shaft resting upon said beams; and a pair of connected complementary clamps having laterally crowned faces fitted to the sides of the shaft over each beam, adapting said shaft for angular adjustment relatively to said beams, said clamps resting on the beams and having means slidably engaging the beam-flanges adapting the clamps for adjustment along said beams.

5. A crown-block comprising spaced, parallel, flanged beams; a sheave-sustaining shaft resting upon said beams; a pair of connected complementary clamps having laterally crowned faces fitted to the sides of the shaft over each beam, adapting said shaft for angular adjustment relatively to said beams, said clamps resting on the beams and having hooks slidably engaging the beam-flanges adapting the clamps for adjustment along said beams; and setscrews for fixing the clamps on the beams in adjusted position.

In testimony whereof I have signed my name to this specification.

WILLIAM B. ROWLAND.
